PROPELLER

Eugene Newnham, St. Louis, Mo., assignor to
 Knapp-Monarch Company, St. Louis, Mo., a
 corporation of Missouri

Application March 9, 1937, Serial No. 129,808

21 Claims. (Cl. 170—173)

An object of my invention is to provide an air propeller for electric fans and the like, such propeller being of simple, durable and inexpensive construction.

5 A further object is to provide a propeller, the blades of which may be integrally or individually formed of sheet or molded rubber or other suitable flexible material, the propeller having a two-part hub, the parts of which engage opposite sides of the blade member and are so formed that they hold the blades thereof at the proper angle for effective air delivery.

Another object is to provide a flexible blade member or a plurality of individual blades and a pair of hub elements, the hub elements having annular flanges of stepped character, the blades being interposed between companion portions of these flanges and held thereby at their proper pitch angle.

20 A further object is to provide a means which connects the two hub elements together and holds them assembled relative to the propeller blade.

25 Still a further object is to provide means for connecting the hub elements with a drive shaft such as the shaft of an electric motor.

With these and other objects in view, my invention consists in the construction, arrangement and combination of the various parts of my propeller, whereby the objects contemplated are attained, as hereinafter more fully set forth, pointed out in my claims, and illustrated in the accompanying drawings, in which:

Figure 1 is a perspective view of a propeller embodying my invention.

Figure 2 is a front elevation of the blade member showing its shape when flat.

Figure 3 is an inside elevation of an outer hub element used in connection with the blade member of Figure 2.

Figure 4 is a front elevation of another hub element which is used in conjunction with the hub element of Figure 3 to support the blade-member.

Figure 5 is a side elevation of the propeller showing the blade projecting toward the observer cut off at the periphery of the hub and shown in section.

Figure 6 is a sectional view on the line 6—6 of Figure 5.

Figure 7 is a similar sectional view showing a modified construction for holding the two parts of the hub together.

Figure 8 is a similar sectional view showing another modified form of securing means.

Figure 9 is a front elevation of the blade member used in connection with the construction shown in Figure 8.

Figure 10 is a view similar to Figure 4 showing another modified construction of hub especially designed for individual blade elements instead of a single blade member having the plurality of blades formed thereof.

Figure 11 is a view similar to Figure 3 showing the companion hub member for the member 10 shown in Figure 10.

Figure 12 is a perspective view of an individual blade member used with the hub elements of Figures 10 and 11.

Figure 13 is a side elevation of the hub elements of Figures 10 and 11 assembled relative to each other with one of the blades in position and cut off at the periphery of the hub and shown in section; and

Figure 14 is a sectional view on the line 14—14 20 of Figure 13.

On the accompanying drawings I have used the reference characters H and H' to indicate hub elements and B a blade member. The blade member B is preferably formed of flexible sheet 25 material stamped out to the shape shown in Figure 2, the material being flat in this figure.

The blade member B comprises blades 10 and central connecting portion 12, the portion 12 being perforated as indicated at 14. The hub 30 element H comprises a disk-like flange 16 and an annular flange 18. The flange 18 is of stepped character, and a portion designated 18' thereof (see Figure 5) is formed at the desired pitch angle for the blades of the propeller.

The hub element H' has an outer domed wall 20 and an annular flange 22. The flange 22 is likewise of stepped character having an angular portion 22' which is of the same contour as the portion 18' of the hub H. These edges 18' and 22' may therefore be termed companion meeting edges as they fit each other with the blade 10 interposed therebetween as shown in Figure 5, particularly by reference to the blade which is shown in section.

Within the hubs H and H' internal hubs or projections 24 and 26 are provided. These project toward each other and are adapted to engage the central portion 12 of the blade member B as shown in Figure 6 when the parts are assembled relative to each other. Suitable means is provided for retaining the hubs H and H' together. In Figure 6 this means consists of a screw 28 extending through a bore 30 of the hub element H', through the opening 14 at the cen-

ter of the blade member B and then into a screw threaded bore 32 of the hub element H. A sleeve 34 extends from the hub H and receives a drive shaft 36. Means such as a set screw 38 is provided for securing the drive shaft in the bore of the sleeve 34.

In Figure 7 the securing means for the hub elements H and H' consists of a tubular sleeve 40 having a head 42. The sleeve 40 extends through a bore 44 of the hub element H, through an enlarged perforation 14' of the blade member B and into a screw threaded bore 46 of the hub element H'. The motor shaft 36 extends into the tubular sleeve 40 and a set screw 38' is used to secure it in position.

In the modification shown in Figure 8, the hub elements H and H' have internal hubs 24' and 26', but the blade member B instead of being provided with a central perforation, is solid at the center and provided with a pair of perforations 14'' spaced radially outwardly from the internal hubs 24' and 26'. The hub element H' is provided with bosses 48 which extend through the openings 14'' and screws 50 are provided for extension through perforations 52 of the hub H and threaded into the bosses 48.

In all forms of the invention, however, the hub elements are formed so that when they are clamped together by any of the securing means disclosed with the blade members between them, the blades 10 are held at the proper pitch angle for effective air delivery upon rotation of the propeller.

The invention is applicable to sheet metal propellers as well as flexible propellers of sheet rubber or the like, although it is especially designed for the flexible type of blade. The hub elements distort the blades so that they assume the proper shape and angle upon assembly and thereafter will retain this shape during operation, except when striking objects whereupon they bend backwardly to avoid damage to either the blades or the objects so struck.

In Figures 10, 11, 13 and 14 I show hub elements H'' and H''' which are particularly designed for mounting a plurality of individual blades B' shown in Figure 12. The hub element H'' comprises a disk 54 and a plurality of flanges 58 similar to the flanges 18 of the hub element H in Figure 4. Likewise the hub element H''' has a plurality of companion flanges 60 similar to the flanges 20 of Figure 3, these being adapted for fitting together in spaced relationship as shown in Figure 13, wherein the blade B' is shown in section between the flanges. Shoulders 62 and 64 limit the movement of the hub element H''' relative to the hub element H'' during assembly so as to not too tightly squeeze the blade B'.

Each blade B' has an enlarged flange 66 at its inner end which fits within the hub when the two parts thereof are assembled as shown in Figure 14, and this prevents outward movement of the blade as a result of centrifugal action during rotation of the propeller within the hub element H'''. A plurality of projections 68 are provided which are arranged inside the flange 66 to prevent any undesired extension of the blade B' inwardly relative to the hub.

The hub elements are secured together by screws 70 and mounted on the motor shaft 36 by a set screw 72. An opening 74 is preferably provided in the hub element H''' through which a shaft for balancing purposes can be projected when, after the propeller is assembled, it is desirable to balance it on knife-edged ways.

The opening 74 is preferably closed by a plug 76 which is frictionally held in the opening and knurled so that it will remain in position after being forced into the opening. The plug 76 preserves the continuity of outline of the hub element H'''.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a propeller, a two-part hub member, a flexible blade member, the two parts of said hub member having a plurality of pairs of companion meeting edges inclined relative to the plane of rotation of the propeller at the desired pitch angle for the propeller blades, one of said two parts being substantially shell-like and the meeting edges thereof being thereby flange-like in character and means for retaining said two parts assembled relative to each other with the blades of said blade member interposed between said meeting edges, the centers of said two portions of said hub member having projections toward each other, the central portion of said flexible blade member spaced from said flange-like meeting edges being interposed therebetween.

2. In a propeller, a two-part hub member, a flexible blade member, the two parts of said hub member having a plurality of pairs of companion meeting edges inclined relative to the plane of rotation of the propeller at the desired pitch angle for the propeller blades and means for retaining said two parts assembled relative to each other with the blades of said blade member interposed between said meeting edges, one of said portions being hollow and the other of said portions having a sleeve projecting into the hollow portion and a drive shaft extending into said sleeve and secured thereto.

3. In a propeller, a pair of hub elements, a blade member comprising a plurality of blades and a central connecting portion, said hub elements having annular flanges of stepped contour and substantially spaced from the peripheries of the hub elements, said hub elements being secured together with the blades of said blade member interposed between said flanges, the portions of the flanges engaging the blades being each inclined at the desired pitch angle for the blade, said hub elements within said flanges having internal hubs projecting toward each other and engaging the central connecting portion of said blade member.

4. In a propeller, a pair of hub elements, a blade member comprising a plurality of blades and a central connecting portion, said hub elements having annular flanges of stepped contour, said hub elements being positioned relative to each other with the blades of the blade member interposed between said flanges, the portions of the flanges engaging the blade being each inclined at the desired pitch angle for the blade, a screw extending through one of said hub elements, through the blade member and threaded into the other hub element to retain the hub elements and the blade member assembled relative to each other, one of said hub elements having a bore therein through which a shaft may be passed for balancing during assembly and a plug for said bore.

5. In a propeller, a pair of hub elements, one

of said elements having a substantially ellipsoidal contour, a blade member comprising a plurality of blades and a central connecting portion, said hub elements having annular flanges of stepped contour, said hub elements being positioned relative to each other with the blades of the blade member interposed between said flanges, the portions of the flanges engaging the blade being each inclined at the desired pitch angle for the blade and a screw extending through one of said hub elements, through the blade member and threaded into the other hub element to retain the hub elements and the blade member assembled relative to each other, said hub elements within said flanges having internal hubs projecting toward each other and engaging the central connecting portion of said blade member, one of said hub elements having a bore therein through which a shaft may be passed for balancing during assembly, and a plug for said bore.

6. In a propeller, a pair of hub elements, a blade member comprising a plurality of blades and a central connecting portion, said hub elements having annular flanges of stepped contour, said hub elements being positioned relative to each other with the blades of the blade member interposed between said flanges, the portions of the flanges engaging the blade each being inclined at the desired pitch angle for the blade, a headed tubular sleeve extending through one hub element and threaded into the other one to retain said hub elements and blade member assembled and a drive shaft extending into said tubular sleeve.

7. In a propeller, a pair of hub elements, a blade member comprising a plurality of blades and a central connecting portion, said hub elements having annular flanges of stepped contour, said hub elements being positioned relative to each other with the blades of the blade member interposed between said flanges, the portions of the flanges engaging the blade being each inclined at the desired pitch angle for the blade, a headed tubular sleeve extending through one hub element and threaded into the other one to retain said hub elements and blade member assembled and a drive shaft extending into said tubular sleeve, said hub elements within said flanges having internal hubs projecting toward each other and engaging the central connecting portion of said blade member.

8. In a propeller, a two-part hub member, a plurality of flexible blades, the two parts of said hub member having annular flanges provided with a plurality of pairs of comparatively narrow companion meeting edges inclined relative to the plane of rotation of the propeller at the desired pitch angle for the propeller blades and forming, when assembled together, an ellipsoidal shaped hub member and means for retaining said two parts assembled relative to each other with said blades interposed between said meeting edges.

9. In a propeller, a pair of hub elements, a plurality of blade elements, said hub elements having annular flanges of stepped contour, said hub elements being positioned relative to each other with said blades interposed between said flanges, the portions of the flanges engaging the blades each being inclined at the desired pitch angle for the blade, the outer hub element having a bore through which the propeller may be balanced and a plug for said bore.

10. In a propeller, a pair of hub elements, a

blade member comprising a plurality of blades and a central connecting portion, said hub elements having annular flanges of stepped contour, said hub elements being positioned relative to each other with the blades of the blade member interposed between said flanges, the portions of the flanges engaging the blade being each inclined at the desired pitch angle for the blade, a headed tubular sleeve extending through one hub element and threaded into the other one to retain said hub elements and blade member assembled and a drive shaft extending into said tubular sleeve, said hub elements within said flanges having internal hubs projecting toward each other and engaging the central connecting portion of said blade member, said blade member having perforations through which said means extends.

11. In a hub assembly for mounting fan blades, a member adapted for mounting on a shaft, said member having substantially annular flanges of stepped contour, a fairing member having substantially annular flanges adapted to substantially interfit with the flanges on said first mentioned member and to have blade members clamped therebetween, tension means for drawing said first mentioned member and said fairing member together for clamping blade members between the flanges thereof, an axial bore through said fairing member through which a shaft may be extended for balancing the assembly during manufacture and a plug for said bore.

12. In a hub assembly for mounting fan blades, a member adapted for mounting on a shaft, said member having substantially annular flanges of stepped contour, a fairing member having substantially annular flanges adapted to substantially interfit with the flanges on said first mentioned member and to have blade members clamped therebetween, tension means for drawing said first mentioned member and said fairing member together for clamping blade members between the flanges thereof, an axial bore through said fairing member through which a shaft may be extended for balancing the assembly during the manufacture, a countersunk portion at the outer end of said bore, and a plug adapted to seat in said countersunk portion and be frictionally held therein and to preserve the continuity of contour of said fairing member.

13. In a hub assembly for mounting fan blades, a member adapted for mounting on a shaft, said member having substantially annular flanges of stepped contour, a fairing member of substantially ellipsoidal contour, said fairing member having substantially annular flanges of stepped contour, said fairing member flanges adapted to substantially interfit with the flanges on said first mentioned member and to have blade members clamped therebetween, tension means for drawing said first mentioned member and said fairing member together for clamping blade members between the flanges thereof, an axial bore through said fairing member through which a shaft may be extended for balancing the assembly during the manufacture, a countersunk portion at the outer end of said bore, and a plug adapted to seat in said countersunk portion and be frictionally held therein and to preserve the continuity of contour of said fairing member.

14. In a propeller, a pair of hub elements, a blade member, said hub elements having stepped peripheries, said hub elements being positioned relative to each other with the blades of the blade member interposed between said peripher-

ies, the portions of the peripheries engaging the blade member each being inclined at the desired pitch angle for the blades, a headed tubular sleeve extending through one hub element and 5 threaded into the other one to retain said hub elements and blade member assembled and a drive shaft extending into said tubular sleeve.

15. In a propeller, a two-part hub member, said two parts, when assembled together, being 10 substantially ellipsoidal shaped, flexible blade means, said two parts having a plurality of pairs of spaced companion edges inclined relative to the plane of rotation of the propeller at the desired pitch angle for the propeller blades, 15 means for retaining said two parts assembled relative to each other with the blades of said blade means interposed between said companion edges and stop shoulders adjacent the ends of said companion edges to limit the size of the space between 20 them.

16. In a propeller of the class described, a pair of hub elements, blade members connected therewith, means for securing said hub elements together with said blade members interposed therebetween, the portions of said hub elements engaging said blade members being each inclined at the desired pitch angle for the blade, said hub elements each having a bore therein, said bores being aligned with each other whereby a shaft 25 may be passed therethrough for balancing the propeller during assembly, and a plug in one of said bores, the outer surface of said plug being shaped to preserve the continuity of the surface of the hub element in which it is mounted.

30 17. In a propeller, a single piece blade member formed of flexible material of generally uniform thickness, said member comprising a plurality of counter-part and equally spaced blades radiating from a centrally perforated central portion of the blade member, a two part hub member co-axial with the blade member and being of larger diameter than said central portion of the blade member, the two parts of said hub member having counter-part companion faces 40 spiralling in the same direction rotationally of the hub member, each pair of said companion faces being similarly curved, said faces being equal in number to said blades and each blade having a similar portion thereof extending between, engaged by and retained curved in cross-section by said companion faces and means co-axial with and extending through the central perforation in the blade member for rigidly clamping said two parts of the hub member together on opposite sides of the blade member.

35 18. A fan comprising a hollow base member having a circumferential flange formed with a plurality of inclined edges, a hollow cap member having a plurality of similarly inclined comple-

5 mental edges, a flexible blade of rubber or the like between each coating pair of inclined edges of the cap and base member, and means for firmly clamping the cap and base member together and gripping the flexible blades between said inclined edges at the proper angle for propelling air when the fan is rotated.

19. A fan comprising a base member, a cap member, said members being formed with complementary inclined gripping portions, means for 10 clamping said members together, and flexible fan blades of rubber or the like gripped and held between said gripping portions, the inclination of said gripping portions being such as to force said flexible blades to and hold them in proper 15 angular relation to each other for propelling air when the fan is rotated, said base member and cap member being hollow and formed of pressed sheet metal, each of said base and cap members being formed with marginal flange-like portions 20 in which the complementary gripping portions are formed.

20. A fan comprising a base member, a cap member, said members being formed with complementary inclined gripping portions, means for 25 clamping said members together, and flexible fan blades of rubber or the like gripped and held between said gripping portions, the inclination of said gripping portions being such as to force said flexible blades to and hold them in proper angular relation to each other for propelling air when the fan is rotated, said base member and cap member being hollow and formed of metal, each of said base and cap members being formed with marginal flange-like portions 30 in which the complementary gripping portions are formed.

21. In a propeller, a single piece blade member formed of flexible material of generally uniform thickness, said member comprising a plurality of counterpart and equally spaced blades radiating 40 from a centrally perforated central portion of the blade member, a two part hub member co-axial with the blade member and being of larger diameter than said central portion of the blade member, the two parts of said hub member having 45 counterpart companion faces spiralling in the same direction rotationally of the hub member, each pair of said companion faces being similarly curved, said faces being equal in number to said blades and each blade having a similar portion thereof extending between, engaged by and formed for air propelling surfaces by said companion faces and means co-axial with and extending through the central perforation in the blade member for rigidly clamping said two 50 parts of the hub member together on opposite sides of the blade member.

EUGENE NEWNHAM.
